UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

FEEDING MECHANISM FOR OVERSEAMING-MACHINES.

1,275,295.

Specification of Letters Patent. Patented Aug. 13, 1918.

Application filed October 28, 1913. Serial No. 797,774.

To all whom it may concern:

Be it known that I, LANSING ONDERDONK, a citizen of the United States, residing at New York, in the county of New York, 5 State of New York, have invented certain new and useful Improvements in Feeding Mechanism for Overseaming-Machines, of which the following is a description, reference being had to the accompanying drawing and to the figures of reference marked thereon.

The invention relates to new and useful improvements in the feeding mechanism for an overseaming machine, and more particularly an overseaming machine known in the art as a "cup feed machine".

An object of the invention is to provide a feeding mechanism for intermittently rotating the feed wheels, which shall be simple 20 in construction and of few parts, positively actuated from an eccentric on the main shaft.

A further object of the invention is to provide a feeding mechanism of the above 25 character with devices for separating the feed wheels to facilitate the insertion or removal of the material.

A still further object of the invention is to provide devices for releasing the tension 30 on the thread for the needle when positioning the feed wheels for the removal of the material.

These and other objects will in part be obvious and will in part be hereinafter more 35 fully disclosed.

In the drawings which show by way of illustration one embodiment of the invention,

Figure 1 is a side elevation with parts in 40 section showing a machine embodying my improvements;

Fig. 2 is a bottom plan view of the same;

Fig. 3 is a front view of the machine, certain parts of the feeding mechanism being 45 shown in dotted lines;

Fig. 4 is a detail in section showing the means for limiting the movement of the bracket supporting the outer feed wheel.

The machine as herein illustrated consists 50 of a main casing 1, in which is mounted a main shaft 2, having a belt wheel 3 at each end thereof. A needle bar 4 reciprocates in the casing and supports a needle 5. A looper 6 cooperates with the needle and said 55 looper is mounted on a looper rod 7, which

is moved so that the looper enters the needle loop at one side of the material and then crosses the material to the opposite side thereof, and presents its loop to the needle. These parts, so far as the present invention 60 is concerned, may be of the usual construction.

The fabric to be stitched is supported in a substantially vertical position by co-operating feed wheels 8 and 9. The feed wheel 8 is carried by a shaft 10, which is mounted in suitable bearings in a bracket 11 carried by the casing 1. The feed wheel 9 is carried by a shaft 12, which is journaled in suitable bearings in a bracket 13. The bracket 13 is 70 pivoted to the bracket 11 by a pivot bolt 14, which extends across the lower part of the brackets. This bolt 14 is rigidly attached to the outer bracket 13, and the bolt turns freely in bearings formed in the inner bracket 11. The inner bracket 11 is bolted rigidly to the casing by suitable bolts 75 15. At the lower end of the shaft 10 is a gear 16, which meshes with a gear 17 rigidly secured to the lower end of the shaft 80 12. These two gears are so proportioned that they turn the feed wheels 8 and 9 in unison, but in opposite directions so that the material to be stitched may be clamped between the feed wheels and held for the 85 stitching mechanism. The material, of course, projects slightly above the feed wheels.

The gears attached to the shafts carrying the feed wheels mesh with each other in a 90 vertical plane passing through the axis of the pivot bolt 14, and this permits the outer bracket to be moved about the pivot bolt without moving the gears out of mesh, and, therefore, the outer bracket may be 95 moved carrying with it, its feed wheel and thereby separate the feed wheels for the removal or insertion of the fabric or material to be stitched. The base of the brackets supporting the feed wheels are shaped so as 100 to house the lower end of the shafts for the feed wheels and the connecting gears. The dividing line between the brackets lies substantially in a vertical plane passing through the axis of the pivot bolt 14. A guard 18 attached to the fixed bracket extends across the dividing line between the bracket and covers the space formed when the outer bracket is moved away from the fixed bracket. This prevents the fabric being 110

stitched from dropping between the brackets and preventing the feed wheels from being brought back into normal operative position relative to each other.

5 The outer bracket is swung on its pivotal axis by an arm 19 which is rigidly attached to said bracket. This arm 19 has a laterally projecting arm 20 which extends through a slot in the casing, and a leaf 10 spring 21 bears on said arm 20. This leaf spring at its opposite end rests on a lug 22, and a screw 23 passing through a lug 24 engages the leaf spring between its ends and may be used for varying the tension of said 15 spring. The adjusting screw 23 may be locked in various adjusted positions by a lock nut 25. The spring bearing on the outer end of the arm 20 normally holds said arm depressed and this yieldingly presses 20 the feed wheels into contact with each other.

The bracket is moved to separate the feed wheels by a lever 26, which is pivoted at 27 to the casing and is formed with a groove which extends underneath the arm 20. This 25 lever is preferably connected to a treadle which, when depressed, raises the arm 20 and thus shifts the bracket to separate the feed wheels.

It is also desirable, when removing the 30 fabric, to release the tension on the needle thread. The tension for the needle thread is shown in Fig. 3, and consists of a fixed rod 28 which is mounted in a lug 29 carried by the casing. On said rod are disks 30, which 35 are pressed together by a spring 31. This spring bears against a plate 32 which in turn bears against the disks. The other end of the spring bears against an adjustable nut 33. This plate 32 has an extended bearing 32^a for the disks and also has a ledge 34. A forked arm 35 extends between this ledge and the disks and is fixed to a rod 36 sliding in ears 37 formed on the supporting lug for the tension. A spring 38 encircles said last 40 named rod and bears against one of said ears and against a fixed collar 39 on the rod. This spring normally presses the collar against the other ear and when in this position the forked arm is so disposed that 45 the spring for the tensions will hold the same in contact. In other words, the forked arm is now out of contact with the ledge on the plate, which forces the tensions together.

It will readily be seen that if the rod carrying the forked arm is forced to the right, as viewed in Fig. 3, the spring for the tensions will be compressed by a movement of the plate away from the tensions, and the tension disks released.

50 This rod for releasing the tension on the needle thread is moved endwise by a rock lever 40, which is pivoted to the casing at 41. One arm of the rock lever bears against the 55 end of the rod, while the other arm of the

rock lever is connected to a link 42, which 65 in turn is connected to the extreme outer end of the lever, which separates the feed wheels. When the lever is depressed this link 42 is raised which swings the rock lever, which, in turn, releases the pressure of 70 the spring on the tension disks.

The feed wheels are intermittently operated to feed the fabric from an eccentric 43 on the main shaft 2. This eccentric 43 cooperates with an eccentric strap 44, which 75 is formed integral with a link 45 pivoted to a ball stud carried by a rock shaft 46. This rock shaft 46 is mounted in suitable lugs 47 on the outer face of the casing. The upper arm 48 of the rock shaft extends through a 80 slot in the casing and carries the ball stud to which said link is pivoted. At the lower end of the rock shaft there is a second arm 49, which is formed with a slot 50. A link 51 is pivoted to a stud 52 which is adjustable in said slot 50. Freely mounted on the shaft carrying the feed wheel 8 is a disk 53, which disk has an outwardly extending arm 54 and the link 51 is pivotally attached to the outer end of this arm. 90

Fixed to said shaft is a collar 55 which is formed with a downwardly projecting flange 56. Said disk 53 has a hub 57 attached thereto which is provided with laterally projecting arms 58, and recesses 59. Friction clamping members 60, as herein shown four in number, are each provided with a slot which receives the flange 56. These slots are slightly wider than the thickness of the flange, so that when said friction 100 members are in a radial position the flange can turn freely through the slots, but a slight movement of these friction members from radial position will cause the side walls of the slots to grip the flange. The inner 105 ends of these friction members rest in the recesses. A spring 61 carried by each arm 58 normally presses against said friction members and tends to force the same to radial position. 110

A movement of the arm in a counter-clockwise direction, as viewed in Fig. 2, will cause the hub to move the inner ends of the clamping members 60, and cause these clamping members to grip the flange 56 and 115 turn the shaft carrying the feed wheel 8, and, through the gear connection between the shafts, also turn the feed wheel 9. In order to prevent a retrograde movement of the shaft, when the arm and disk are moving in a clockwise direction, I have provided a friction member 62 which is also formed with a similar groove edging over the flange 56. This friction gripping member has its outer end extending into a recess 120 63 in a bracket 64. A spring 65 bears against this friction member and normally holds the same out of gripping contact with the 125

flange, when said flange is moved in proper direction to feed the fabric, but said gripping member engages the flange and prevents a backward movement of the feed 5 wheel when the friction members are moved backward for gripping the flange for the next feed movement.

An adjustable screw 61 passes through the frame directly below the arm 20 and 10 limits the downward movement of said arm through the action of the leaf spring 21. An adjustable screw 62 also passes through the frame and limits the upward movement of the arm 20, and this limits the outward 15 throw of the bracket 12 when the outer end of the lever 26 is depressed.

While I have stated that my present invention is directed to a feeding mechanism, it will be understood that I have used this 20 term in its broadest sense, and as covering not only the actual feed of the fabric, but the mechanism for shifting the feed wheels to permit the removal or insertion of the fabric, and also the mechanism which operates 25 to release the tension so that the fabric may be quickly withdrawn from the machine.

It is obvious that minor changes in the details of construction and the arrangement 30 of parts may be made without departing from the spirit of the invention, as set forth in the appended claims.

Having thus described my invention, what I claim is:

1. A sewing machine including in combination a casing, a main shaft extending into said casing, stitch forming mechanism, feed wheels for supporting and feeding a fabric in substantially a vertical plane to the stitch forming mechanism, and means for actuating 40 said feed wheels including a vertically disposed rock shaft, an arm fixed to said rock shaft at the upper end thereof, means actuated by the main shaft for oscillating said arm, an arm connected to the lower end 45 of said rock shaft, and devices actuated thereby for intermittently rotating the feed wheels, said last named devices being adjustable whereby the throw of the feed wheels may be varied.

2. A sewing machine including in combination a casing, a main shaft extending into said casing, stitch forming mechanism, feed wheels for supporting and feeding a fabric in substantially a vertical plane to 55 the stitch forming mechanism, and means for actuating said feed wheels including a vertically disposed shaft, bearings on the outer face of said casing in which said shaft is journaled, an arm carried by the upper end of said shaft and extending through a slot in said casing to the inside thereof, an eccentric on the main shaft connected to said arm for oscillating said vertical shaft, an arm at the lower end of said vertical shaft

extending in a direction substantially parallel to one wall of the casing, and devices operated by said last named arm for intermittently rotating said feed wheels. 65

3. A sewing machine including in combination a casing, a main shaft extending into 70 said casing, stitch forming mechanism, feed wheels for supporting and feeding a fabric in substantially a vertical plane to the stitch forming mechanism, and means for actuating said feed wheels including a vertically 75 disposed shaft, bearings on the outer face of said casing in which said shaft is journaled, an arm carried by the upper end of said shaft and extending through a slot in said casing to the inside thereof, an eccentric 80 on the main shaft connected to said arm for oscillating said vertical shaft, an arm at the lower end of said vertical shaft extending in a direction substantially parallel to one wall of the casing, and devices operated by said 85 last named arm for intermittently rotating said feed wheels, said devices including a link having an adjustable connection with the lower arm whereby the throw of the feed wheels may be varied. 90

4. A sewing machine including in combination a casing, a main shaft extending into 95 said casing, stitch forming mechanism, feed wheels for supporting and feeding a fabric in substantially a vertical plane to the stitch forming mechanism, and means for actuating said feed wheels including a vertically 100 disposed shaft, bearings on the outer face of said casing in which said shaft is journaled, an arm carried by the upper end of said shaft and extending through a slot in said casing to the inside thereof, an eccentric on the main shaft connected to said arm for oscillating said vertical shaft, an arm at the lower end of said vertical shaft extending in a direction substantially parallel to one wall of the casing, and devices operated by said 105 last named arm for intermittently rotating said feed wheels, said devices including a link adjustably connected with said arm and extending through a slot in said casing, and devices connected to the other end of said link for intermittently rotating the feed wheels. 110

5. A sewing machine including in combination a casing, a main shaft extending into 115 said casing, stitch forming mechanism, feed wheels for supporting and feeding a fabric in substantially a vertical plane to the stitch forming mechanism, and means for actuating said feed wheels including a vertically 120 disposed shaft, bearings on the outer face of said casing in which said shaft is journaled, an arm carried by the upper end of said shaft and extending through a slot in said casing to the inside thereof, an eccentric 125 on the main shaft connected to said arm for oscillating said vertical shaft, an arm at the

lower end of said vertical shaft extending in a direction substantially parallel to one wall of the casing, and devices operated by said last named arm for intermittently rotating said feed wheels, said last named devices including an oscillating disk and friction gripping members controlled thereby, and a friction gripping member for preventing a retrograde movement of the feed 10 wheels.

6. A sewing machine including in combination a casing, a main shaft extending into the casing, stitch forming mechanism operated by said main shaft, opposed feed wheels 15 for supporting and feeding the fabric in substantially a vertical plane to the stitch forming mechanism, a bracket fixed to the casing, a shaft located in said bracket and supporting one of said wheels, means for intermittently rotating said shaft from the main shaft, a bracket pivoted to said casing, a shaft supporting the other feed wheel journaled in said pivoted bracket, gears for connecting the lower ends of the shafts for the 20 feed wheels, the pivotal connection between said brackets consisting of a rod fixed to the outer bracket and freely journaled on the inner bracket, means connected to said rod for oscillating the same, to move the outer 25 bracket to separate the feed wheels, and a leaf spring operating through said rod for moving said pivoted bracket to normally hold said feed wheels in gripping contact, and means whereby the tension of said leaf 30 spring may be varied.

7. A sewing machine including in combination a casing, a bracket secured to said casing, a feed wheel, a shaft supporting said feed wheel journaled in said bracket, a second bracket pivoted to the first named 40 bracket, a feed wheel, a shaft supporting said last named feed wheel, journaled in said pivoted bracket, gears for connecting the feed shafts, said brackets being formed

so as to house said gears and having their meeting edges located in substantially a vertical plane passing between the feed wheels, and a guard connected to one of said brackets and extending over the edge of the other whereby the space between the meeting 50 edges of the brackets will be covered.

8. A sewing machine including in combination a casing, a main shaft extending into said casing, stitch forming mechanism, feed wheels for supporting and feeding a fabric 55 in substantially a vertical plane to the stitch-forming mechanism, and means for actuating said feed wheels including a vertically disposed shaft, bearings on one face of the casing in which said shaft is journaled, an 60 arm carried by the upper end of the shaft, an eccentric on the main shaft connected to said arm for oscillating said vertical shaft, an arm at the lower end of said vertical shaft, and devices operated by said last 65 named arm for intermittently rotating said feed wheels, said devices being adjustably connected to said last-named arm whereby the throw of the feed wheel may be varied.

9. A sewing machine including in combination a casing, feed wheels for feeding the fabric, vertical shafts for supporting the feed wheels, a bracket pivoted to the casing for supporting the outer feed wheel, an arm attached to the bracket for swinging the 75 same, a spring for normally pressing said bracket for holding said feed wheels in normal operative position, an adjustable stop for limiting the movement of the bracket by the action of the spring, and an adjustable 80 stop for limiting the outward movement of the bracket.

In testimony whereof, I affix my signature, in the presence of two witnesses.

LANSING ONDERDONK.
